CLAIM

The ornamental design for a remote control, as shown and described.

DESCRIPTION

1.1 : Front View;

1.2 : Back View;

1.3 : Left View;

1.4 : Right View;

1.5 : Top View;

1.6 : Bottom View;

1.7 : Top Perspective view;

1.8 : Bottom Perspective view.

1 Claim, 8 Drawing Sheets
